CLAIM

The ornamental design for a cordless portable telephone with faceplate, as shown and described.

DESCRIPTION

FIG. 1 is a right, front, top view of a cordless portable telephone with faceplate showing our new design, the faceplate in a closed position;

FIG. 2 is a right, front, top view thereof, the faceplate in an open position;

FIG. 3 is a rear plan view thereof in a closed position;

FIG. 4 is a left side plan view thereof and in a closed position; and,

FIG. 5 is a bottom plan view thereof in a closed position. The broken lines shown in FIGS. 1-5 are for illustrative purposes only and form no part of the claimed design.
